(57) **CLAIM**

The ornamental design for a modular floor tile with diamond plate surface, as shown and described.

DESCRIPTION

FIG. 1 is a top perspective view of a modular floor tile with a diamond plate surface according to the present invention; FIG. 2 is a top view of the modular floor tile with diamond plate surface of FIG. 1;

FIG. 3 is a bottom view of the modular floor tile with diamond plate surface of FIG. 1;

FIG. 4 is a left side elevation view of the modular floor tile with diamond plate surface of FIG. 1;

FIG. 5 is a right side elevation view of the modular floor tile with diamond plate surface of FIG. 1;

FIG. 6 is a front elevation view of the modular floor tile with diamond plate surface of FIG. 1;

FIG. 7 is a rear elevation view of the modular floor tile with diamond plate surface of FIG. 1;

FIG. 8 is a perspective view of an alternative embodiment of a modular floor tile with diamond plate surface according to the present invention;

FIG. 9 is a top view of the modular floor tile with diamond plate surface of FIG. 8;

FIG. 10 is a bottom view of the modular floor tile with diamond plate surface of FIG. 8;

FIG. 11 is a left side elevation view of the modular floor tile with diamond plate surface of FIG. 8;

FIG. 12 is a rear elevation view of the modular floor tile with diamond plate surface of FIG. 8;

FIG. 13 is a front elevational view of the modular floor tile with diamond plate surface of FIG. 8; and,

FIG. 14 is a rear elevation view of the modular floor tile with diamond plate surface of FIG. 8.
